United States Patent Office

Des. 232,683
Patented Sept. 10, 1974

232,683

STRAND OF BEADS FOR CURTAIN ELEMENTS OR THE LIKE

Irving Levine, 23555 Park Belmonte,
Calabasas Park, Calif. 91302

Filed Nov. 10, 1972, Ser. No. 305,604

Term of patent 14 years

Int. Cl. D6—10

U.S. Cl. D6—205

Fig. 1.

Fig. 2.

Fig. 3.

FIG. 1 is a side elevational view of a strand of beads for curtain elements or the like showing my new design, the bead units repeating, in the sequence shown, to an indeterminate length;

FIG. 2 is a top plan view thereof taken in the direction of the line 2—2 on FIG. 1; and

FIG. 3 is a top plan view taken in the direction of the line 3—3 on FIG. 1.

I claim:

The ornamental design for a strand of beads for curtain elements or the like, substantially as shown and described.
